(57) **CLAIM**

The ornamental design for a moisturizer bar as shown and described.

DESCRIPTION

FIG. 1 is a top perspective view showing my new design for a moisturizer bar.

FIG. 2 is a bottom perspective view thereof.

FIG. 3 is a front view thereof.

FIG. 4 is a back view thereof.

FIG. 5 is a right side view thereof.

FIG. 6 is a left side view thereof.

FIG. 7 is a top view thereof; and,

FIG. 8 is a bottom view thereof.

The broken lines show portions of the moisturizer bar that form no part of the claimed design.

The shade lines in the Figures show contour and do not claim surface ornamentation or treatment.

1 Claim, 8 Drawing Sheets
